SHOE HEEL AND SOLE ASSEMBLY AND METHOD

Filed June 11, 1958

INVENTOR: *28*
JACK MELTZER
BY *Frederick Freudentfeld*
ATTORNEY

the shoe presents a soft and comfortable surface to the foot of the wearer. Moreover, the heel presents a slightly higher appearance than would ordinarily be the case, and this is a desirable feature of ornamentation.

The modification of the invention illustrated in Figs. 2, 7 and 8 involves the employment of a platform element 27 which is laid over the outer sole 28 after the heel fasteners 29 have been applied. In this case, as before, the fasteners 29 extend through a stiff element 30 and a metal shank stiffener 31. The heel cover 32 is in this case provided with an upper margin 33 which extends upwardly to envelop not only the heel part of the sole 28, but also the edges of the platform element 27. This platform element may be of any desired character, composed of a single piece (as shown) or of a padding or the like enclosed within a covering. The heel cover margin 33 is turned in to lie upon the top surface of the platform element 27, and then a sock lining 34 is adhesively applied to the element 27 and to the inturned heel cover margin 33. In this case the sock lining 34 may be a relatively thin piece of appropriate material, although if added height or additional comfort is desired the sock lining might be of the padded variety shown in Figs. 4 and 5.

The construction shown in Figs. 2, 7 and 8 involves, as before, the split-away flap 35 at the rear end of the sole 28, this flap being adhesively secured over the curved heel breast.

It should be understood that the representation of the parts in the accompanying figures is somewhat exaggerated, to clarify the disclosure. In practice, the edges of the rear or heel part of the sole, and the edges of the platform element itself, may be somewhat thinned in the region where the heel cover margin 33 envelops them. The shaping and proportion of the several parts may also be somewhat different in practice, to impart desired ornamental lines and contours to the shoe as a whole.

The shoe depicted in Fig. 2 is provided with an upper which consists of an open-work series of straps 36 in the vamp region, and a rear heel-engaging strap 37. In Fig. 3, a construction is shown which is a modification of the shoe in Fig. 2, in that the upper 38 is arranged only in the forward part of the shoe. In this case the heel cover 39 is extended at its forward end, as indicated at 40, to envelop the edge of the sole 41 in the region directly in front of the heel proper. Where a platform element is employed, the part 40 of the heel cover extends also around the edges of this element, as will be readily understood.

In general, it will be understood that the details herein described and illustrated may in many respects be modified by those skilled in the art without necessarily depart-

ing from the spirit and scope of the invention as expressed in the appended claims.

What is claimed is:

1. In a shoe, a heel, an outer sole whose rear end has an edge conforming in peripheral size and contour to the upper edge of the heel, fasteners extending downwardly through said rear end of the sole into said heel, a platform above said sole and conforming thereto in peripheral contour, a sock lining, and a heel cover snugly enclosing the rear and side walls of the heel and having an upper margin extending upwardly to enclose the edge of said rear end of the sole and also the edge of said platform, the upper edge of said heel cover margin being turned in to lie beneath said sock lining.

2. In the method of making an unlasted shoe, the steps which comprise: providing an upper, a sole, a heel and heel cover, and a sock lining, the sole having its rear end peripherally configured to conform in size and contour to the upper edge of the heel, attaching the upper to the sole in the forward region thereof, applying the heel cover to the heel so that it snugly encloses the rear and side walls and provides a margin extending upward beyond the upper heel edge, seating the rear end of the sole on the heel so that it is closely conformably received within the upwardly extending margin of the heel cover, applying fasteners which enter the exposed surface of the rear end of the sole and pass completely through the sole into the heel to fixedly secure the sole to the heel, subsequently turning in the upwardly extending cover margin to cover the adjacent peripheral edge of the sole and overlie the upper surface of the sole, securing the in-turned portion of the cover margin to the upper surface of the sole, and securing the sock lining to the upper surface of the sole to hide the fasteners and the in-turned portion of the cover margin.
